D12-203. OR D 13,638 EX

DESIGN FOR A STEP-PAD.

Design No. 13,638, dated February 20, 1883.

Perfect

*Diamond shaped one position
Square shaped other position*

UNITED STATES PATENT OFFICE.

JOHN L. POPE, OF CLEVELAND, OHIO.

DESIGN FOR A STEP-PAD.

SPECIFICATION forming part of Design No. 13,638, dated February 20, 1883.

Application filed November 28, 1882. Term of patent 14 years.

To all whom it may concern:

Be it known that I, JOHN L. POPE, of Cleveland, in the county of Cuyahoga and State of Ohio, have invented and produced a new and original Design for Step-Pads, of which the following is a specification, reference being had to the accompanying photograph, making a part thereof.

My invention relates to a design for step-pads, such as used on carriages and other vehicles; and it consists in certain features of ornamentation, which will be hereinafter more fully described, and particularly pointed out in the claims hereof.

In the photograph which accompanies this specification is illustrated, in top view, a step-pad embracing the features of my new design. The general shape of the step is rectangular, and all around its sides and ends, quite near the edges, runs a raised border, to which I have applied the letter *a*. The space inclosed by this border I have beautified by employing bars or ribs and arranging them diagonally of the plate, so as to form a series of rows of contiguous diamond-shaped figures, *b*, when viewed from either the sides or ends of the plate, and rows or columns of square-shaped figures when viewed from any of the four corners of the pad or plate, as plain upon visual inspec-

tion of the photograph. I have perforated each one of the figures *b*, and have thereby considerably improved the appearance of the article, yet a plate may be made without these perforations and still retain the gist of my novel design, which rests particularly in the employment of ribs or bars forming a series of adjoining figures, such as indicated by the letter *b*. The intersecting bars forming the figures marked *b* are, as will be observed, bevelled from the top downward and outward.

What I therefore claim as my invention, and desire to secure by Design Letters Patent, is—

1. A step-pad of substantially the design shown and described.
2. A step-pad the upper surface of which has ornamentation composed of figures substantially like those marked with the letter *b*.
3. A step-pad the upper surface of which is ornamented with figures substantially like those marked *b*, and with a raised border substantially like that marked *a*.

In witness whereof I have hereunto set my hand this 16th day of November, 1882.

JOHN L. POPE.

In presence of—

WALTER A. BIDDLE,
H. CLARK FORD.
